DESIGN FOR A MUFF

Albert Dorfman, New York, N. Y.

Application June 7, 1940, Serial No. 92,887

Term of patent 3½ years

To all whom it may concern:

Be it known that I, Albert Dorfman, a citizen of the United States and resident of New York city, in the county of New York and State of New York, have invented a new, original, and ornamental design for a Muff, of which the following is a specification, reference being had to the accompanying drawing, forming a part thereof.

Fig. 1 is a front elevational view of a muff, showing my new design.

Fig. 2 is a rear elevational view of the same.

Fig. 3 is a top plan view of the same.

Fig. 4 is a front end elevational view of the same.

I claim:

The ornamental design for a muff, as shown.

ALBERT DORFMAN.
